Specification of Letters Patent. Patented Oct. 27, 1914.

Application filed January 4, 1911. Serial No. 600,803.

To all whom it may concern:

Be it known that I, FRANKLIN J. PERKINS, a citizen of the United States, residing in Woburn, county of Middlesex, and State of Massachusetts, have invented an Improvement in Presses, of which the following description, in connection with the accompanying drawings, is a specification, like letters on the drawings representing like parts.

10 This invention relates to presses of that class in which fluid pressure is employed to move one of the platens toward the other, and is herein shown as embodied in a press in which the lower platen is supported by 15 a piston or ram of substantially large diameter, which is initially moved by a piston or plunger of smaller diameter.

The present invention has for its object to provide a simple, efficient and quick-acting 20 press of the character described, and one in which the pressure upon the work or material may be maintained at any desired point for any desired length of time irrespective of the position of the fluid-operated platen.

25 The invention has for its object to provide a press of the character described in which the fluid is circulated in a normally open circuit controlled by a single starting valve, which is manually operated as will be described and has provision for balancing the valve when it is desired to open the same, whereby the said valve may be quickly and easily opened by the operator as will be described. Provision is also made for automatically connecting the cylinder of larger 30 diameter with the fluid supply when the pressure in the cylinder of smaller diameter reaches a predetermined point. Provision is further made for enabling the fluid-operated 35 platen to be successively moved into its operative position in a minimum time, as will be described.

These and other features of this invention will be pointed out in the claims at the end 40 of this specification.

Figure 1 is a front elevation of one form of fluid operated press embodying this invention. Fig. 2, a side elevation looking toward the left in Fig. 1. Fig. 3, a side elevation looking toward the right in Fig. 1. Fig. 3a, a detail to be referred to. Fig. 4, a detail in section and elevation on an enlarged 45 scale showing the main ram, its co-operating

plunger and the starting valve, to be referred to. Fig. 5, a detail on an enlarged 55 scale of the automatic valve controlling the connection of the large cylinder with the fluid supply, and Fig. 6, a diagrammatic view to illustrate the circuit of the fluid.

Referring to the drawing, *a* represents 60 the upper platen and *b* the lower platen of a press embodying this invention and especially adapted among other uses for pressing leather and like material.

In the press herein shown, the upper 65 platen *a* is stationary, it being suitably attached to a cross head or frame *c* sustained by side columns, posts or rods *d*, which are suitably attached to a supporting base *e*. The lower platen *b* is fluid-operated and in 70 the present instance it rests upon a piston or ram *f* (see Fig. 4) of substantially large diameter located in a cylinder *g*, and has co-operating with it a plunger or auxiliary piston *h* of materially smaller diameter, which 75 is located in a cylinder *i*, which will be hereinafter referred to as the small cylinder. The cylinders *g*, *i* are supported by a frame *j*, which is removably secured to the upper 80 surface of the base *e*.

The lower platen *b* preferably has provision for tilting on the ram *f* so as to adjust itself to work of uneven thickness, and as shown in Fig. 4, the platen *b* is provided on its under side with a spherical projection 85 or ball 10, which fits into a curved socket 12 in the upper surface of the ram *f*. The smaller piston *h* is employed to initially move the ram *f* and cause the latter to act as a pump for a portion of its stroke until 90

the pressure of the fluid in the small cylinder reaches a predetermined point, whereupon, said pressure is admitted directly into the large cylinder *g* and thereafter the platen *b* is moved toward the platen *a* by 95 fluid pressure exerted on both pistons. To this end, the small cylinder *i* is provided with a pipe 14, which serves as a fluid inlet and a fluid outlet for the said cylinder, said pipe being connected with a normally open 100 fluid circulating system, which comprises in the present instance, as shown in Fig. 6, a pump 15 of any suitable construction, a source of fluid supply, such as a tank or reservoir 16, a valve casing 17 connected 105 with the pump 15 by a pipe 18, and with

the pipe 14 by a pipe 19, and a second valve casing 20, which is connected by a pipe 21 with the inlet pipe 14 for the small cylinder, and with the supply tank 16 by a pipe 22, and with the inlet pipe 23 for the large cylinder by a pipe 24 containing a check valve 25 of known construction. The pipe 23 is also connected with the supply tank 16 by a pipe 26 containing a check valve 63 of known construction, and the pipe 26 is connected by the pipe 28 with the valve casing 17 for a purpose as will be described.

The valve casing 20 contains a valve, which may be designated the starting valve, and which is shown in Fig. 4 as a hollow cylinder 30 having the fixed bottom 31, which forms the valve proper, and a removable head 32 provided with ports 33 extended through it, and having a valve stem 34, which is extended loosely through the head 32 so as to be capable of movement independently of the valve, for a purpose as will be described. The valve stem 34 above and below the head 32 has fast on it nuts 35, 36, which are designed to be brought into engagement with the head 32 and effect movement of the valve cylinder 30 in opposite directions. The valve stem 34 at its lower end coöperates with a port 37 extended through the valve 31 so as to close and open said port and forms an auxiliary valve, for a purpose as will be described. The valve stem 34 is operatively connected to a starting mechanism, herein shown as a lever 38 on a rock shaft 39 located at the front of the machine, (see Fig. 1), and supported in bearings 40 affixed to the cross head *c*, said rock-shaft having a crank 41, which is connected by a link 42 (see Fig. 3) to one arm 43 of an elbow lever, to the other arm 44 of which the valve stem 34 is connected by a link 45, which in the present instance is forked at its lower end to straddle the valve stem 34 (see Fig. 1), and is 45 pivotally engaged with a collar 46 loose on the valve stem and practically rendered fast thereon by a helical spring 48, which encircles the valve stem between a fixed collar 49 and the loose collar 46 and serves to normally keep the latter in engagement with a collar 50 fixed on the valve stem. The valve stem 34 is extended loosely through a bracket or guide arm 51 attached to the frame of the machine. As represented in Figs. 1 and 3, the operating lever 38 and the parts connected with it, are in the position they occupy when the starting valve is open.

When the starting valve is in its open position shown in Fig. 4, the circulating system is open and the fluid merely circulates therein, and at such time, the lower platen *b* is in its lowered or open position, and the pistons *f*, *h* are in their lowered position shown in Fig. 4. The course of the fluid

under these conditions may be traced in Fig. 6 as follows: from the supply tank 16 by pipe 52 to pump 15, thence by pipe 18 to valve casing 17, thence by pipes 19, 21, to valve casing 20, thence by pipe 22 back to the supply tank 16. The fluid also fills the inlet pipe 14 for the lower cylinder, but does not move its plunger *h*, and it also fills the pipe 24 back to the check valve 25, which is arranged to open in the direction of the arrow 55. When the operating lever 38 is lowered or moved in the direction of the arrow 60 in Fig. 3, the valve rod 34 is first moved to close the port 37 and at such time the nut 35 is brought into engagement with the head 32 and the nut 36 is lowered therefrom. On the continued downward movement of the valve stem 34, the valve 31 is moved with it and is seated to close the exhaust port 61 with which the pipe 22 communicates. The closing of the valve 31 interrupts the circulation of the fluid and causes the same to flow into the small cylinder *i* and raise the piston or plunger *h* therein. The plunger *h* on its upward movement, lifts the ram or large piston *f* and moves the lower platen toward the upper platen. The ram *f* on its upward movement acts as the piston of a suction pump for a predetermined portion of its stroke 90 and draws fluid from the tank 16 through the pipes 26, 23, into the large cylinder, the check valve 63 in the pipe 26 opening in the direction of the arrow 64, Fig. 6, and the check valve 25 being held closed by the pressure of the fluid in the pipe 24, which is connected with the pipe 21 through ports 65 in the cylinder 30 of the starting valve 31 (see Fig. 4). The lower platen *b* continues to be raised by the fluid pressure on its piston *h*, and the large piston or ram *f* continues to act as a suction pump, until the fluid pressure acting on the small piston *h* reaches a predetermined point, whereupon said pressure acts on the valve within the 110 casing 17 and automatically opens said valve and connects the large cylinder *g* with the pressure system, namely, with the pump, whereupon the latter pumps the fluid into the large cylinder and applies the fluid pressure to the large piston or ram *f* and thereby subjects the work to the desired or required pressure.

In Fig. 5, I have shown one construction of automatic valve mechanism, which I may prefer, and which consists of the valve 70 located in a chamber 71 within the casing 17 and coöperating with a port or opening 72 in a partition wall 73, which forms a chamber 74 above it. The lower chamber 71 has 125 connected to it the pipes 18, 19, and the upper chamber 74 has the pipe 28 connected to it. The valve 70 is provided with an enlarged lower portion 75, which practically forms a piston of larger area than the valve, 130

so that when the pressure in the chamber 71 reaches a predetermined point, it will act on said piston and force the same and its attached valve downward and thereby open 5 the valve and connect the chamber 71 with the chamber 74, which allows the fluid under pressure to be forced through the pipes 28, 26, 23 into the large cylinder *g*, wherein it acts directly on the large piston *f* therein. 10 The pressure at which the valve 70 is opened is determined by the tension or strength of a helical spring 80 (see Fig. 2), which encircles the stem 81 of the valve 70 below the casing 17 and is supported at its lower end 15 by a bracket or arm 83 attached to the base *e* and bears at its upper end against a nut 84 on the valve stem. The valve stem 81 may also be provided below the bracket or arm 83 with a nut 85, which acts as a stop to prevent injury to the valve 70 when the latter is seated by the spring 80. By means of the nut 84, the tension or strength of the spring 80 can be adjusted according to the pressure at which it is desired the valve 70 20 should be opened. When the fluid pressure is admitted to the large cylinder *g*, it closes the check valve 63 and cuts off the cylinder *g* from the supply tank 16. The pump then forces the fluid under pressure into both cylinders, and the lower platen *b* forces the material or work against the upper platen and subjects the work to the desired pressure, which is made known to the operator by the 25 gage 87 connected by the pipe 88 with the large cylinder *g*.

When the pressure in the main or large cylinder *g* reaches the maximum amount to which the press is adjusted, which is determined by any suitable relief valve 100 in 30 the pipe 18, the work may be immediately relieved from said maximum pressure, or it may be allowed to remain under said pressure for any desired length of time. When it is desired to immediately relieve the work 35 from the desired pressure, the starting valve is opened wide and to enable the operator to manually open the starting valve from its closed position, in which it may be held to its seat by a fluid pressure of many tons, as for instance 70 tons, the valve stem 34 is 40 made movable independently of the valve as above described, so that, when the operator turns the operating lever 38 upwardly, the valve stem 34 will be lifted so as to uncover the port 37 in the valve and allow the fluid pressure to flow into the exhaust pipe 22 and thereby balance or substantially balance the starting valve, which can then be 45 easily lifted from its seat, to connect the cylinders *g*, *i*, with the exhaust pipe 22, which allows the pistons *f*, *h*, to descend by gravity. As the piston *f* descends, the fluid flows through the pipe 23, check valve 25 and pipe 24, to the valve casing 20 and thence to the exhaust pipe 22, and the fluid 50

in the small cylinder *i* flows through the pipes 14, 21, to the valve casing 20 and thence to the exhaust pipe 22.

In many instances, it may be desired to keep the work under a given pressure less 70 than the maximum for a substantially long time, and this result may be accomplished with the press herein shown, by opening the auxiliary valve 34 of the starting valve less than its full distance and without unseating 75 the main valve 30, so as to effect a balance between the quantity or amount of fluid supplied to the cylinders and the quantity or amount of fluid which flows through the port 37 in the main valve 30. To illustrate, 80 let it be supposed that it is desired to subject a pile of skins to a continuous pressure of say fifty tons for a number of hours. In this case, the press is started by closing the starting valve as above described, and when 85 the gage 87 shows that a pressure of fifty tons has been obtained in the cylinder *g*, the operator raises the lever 38 so as to partially open the auxiliary valve 34, without lifting the valve 30 from its seat, that is, until 90 the valve 34 has been opened a sufficient amount to discharge through the port 37 in the main valve 30 a quantity of fluid equal to the quantity supplied by the pump, or in other words effect a balance between the 95 fluid supplied and the fluid discharged, whereupon the circulation of the fluid in the circuit or system is established and maintained with a pressure of fifty tons on the lower platen. This pressure of fifty tons on 100 the skins or other material may be maintained indefinitely or as long as the circulation is maintained, and in case the material or work is in such condition that it is gradually compressed, as in the case of moisture 105 being present in the material, the lower platen is moved toward the upper platen by a fluid pressure of fifty tons, and the displacement of the piston *h* in its cylinder is compensated for by the increase in volume 110 of the fluid until the moisture has been expressed. The same principle of effecting a balance between the water supplied to the circulating system and that discharged therefrom can be used to control the up- 115ward travel of the lower platen, so that the latter can be stopped in any part of its up-ward travel. This feature is useful in that the lower platen can be stopped in its up-ward travel so as to adjust the work before the pressure is applied, which saves loss of time in dropping the platen and raising it again. In this case, the amount of pressure kept in the cylinder is equal to the weight 120 of the platen only.

In order to quicken the action of the press, the pipe 21 connecting the inlet pipe 14 for the small cylinder with the valve casing 20, is made of smaller diameter than the inlet pipe 14 to choke the flow of fluid 130

- 4
- out of the small cylinder, so that when the said cylinder is connected with the exhaust pipe 22 and the circulation again established, a small volume of fluid is allowed 5 to escape to the exhaust, and the circulating system from the inlet pipe 14 back to the pump is not emptied each time the starting valve is opened, but is maintained filled or substantially filled with fluid, and as a result 10 when the starting valve is again closed, the fluid immediately acts on the piston *h* and the time which would otherwise be required for the pump to fill the system between it and the small cylinder is saved. 15 This is an important feature from a practical standpoint, as it enables the press to perform a greater amount of work in a given time.

Claims.

- 20 1. In a machine of the class described, in combination, a movable platen, a platen co-operating therewith, a piston to move said movable platen, a main cylinder in which said piston is located, a starting piston co-operating with said first-mentioned piston, a cylinder in which said starting piston is located, a normally open fluid circulating system including a source of fluid supply, a pump, pipe connections between said pump and fluid supply to enable the pump to take fluid therefrom and return it thereto, means for connecting the cylinder of the starting piston with said circulating system, a starting valve controlling the circulation of fluid, 25 a second valve included in said circulating system and automatically operated when the pressure in the starting cylinder reaches a predetermined point to admit fluid pressure into the said main cylinder, means independent of the circulating system for connecting the main cylinder with the source of fluid to draw fluid into the main cylinder, and means to shut off the main cylinder from said source of supply when fluid under pressure is admitted into said main cylinder, substantially as described. 30
2. In a machine of the class described, in combination, a movable platen, a platen co-operating therewith, a piston to move said movable platen toward its co-operating platen, a cylinder in which said piston is located, a normally open fluid circulating system with which said cylinder communicates; means for circulating fluid through said system without effecting movement of said piston, a valve casing included in said system, a valve in said casing for interrupting the circulation of fluid in said system and cause the fluid pressure to act on said piston, said valve having a port or opening, a valve rod or stem for said valve co-operating with said port, and means to operatively connect said valve rod with said valve to move the latter and to permit the valve rod to be moved independently of

the valve to open said port and substantially balance said valve, for the purpose specified.

3. In a machine of the class described, in combination, a movable platen, a platen co-operating therewith, a piston to move said movable platen toward its co-operating platen, a cylinder in which said piston is located, a normally open fluid circulating system with which said cylinder communicates, means for circulating fluid in said system without operating the movable platen, a valve casing in said system on the exhaust side of the said cylinder, and a valve in said casing for controlling the flow of fluid from the pressure side to the exhaust side of said system, said valve comprising a main valve having a port, and an auxiliary valve co-operating with said port, said main valve being constructed to remain seated until positively lifted by the auxiliary valve, manually operated means for operating said auxiliary valve whereby the said piston may be relieved from pressure substantially in an instant or may be subjected to a selected pressure less than the maximum capacity of the apparatus for any desired length of time, substantially as described. 85

4. In a machine of the class described, in combination, a movable platen, a platen co-operating therewith, a piston to move said movable platen, a main cylinder in which said piston is located, a starting piston co-operating with said first-mentioned piston, a cylinder in which said starting piston is located, a normally open fluid circulating system with which said starting cylinder is connected, means for circulating fluid in said system without effecting movement of the starting piston, a valve casing included in said system on the exhaust side of said starting cylinder, a valve in said casing to interrupt the fluid circulation and cause fluid pressure to act on the starting piston, substantially as described. 100 105

5. In a machine of the class described, in combination, a movable platen, a platen co-operating therewith, a piston to move said movable platen, a main cylinder in which said piston is located, a starting piston co-operating with said first-mentioned piston, a cylinder in which said starting piston is located, a normally open fluid circulating system with which said starting cylinder is connected, means for circulating fluid in said system without effecting movement of the starting piston, a valve casing included in said system on the exhaust side of said starting cylinder, a valve in said casing to interrupt the fluid circulation and cause fluid pressure to act on the starting piston, a valve casing included in said system on the inlet side of said cylinder, means for connecting said second casing with the main cylinder, and a valve in said second casing 110 115 120 125 130

normally cutting off the main cylinder from the said casing and automatically opened when the pressure within its casing reaches a predetermined point, substantially as described.

6. In a machine of the class described, in combination, a movable platen, a platen co-operating therewith, a piston to move said movable platen, a main cylinder in which 10 said piston is located, a starting piston co-operating with said first-mentioned piston, a cylinder in which said starting piston is located, a normally open fluid circulating system, a pump in said system for circulating fluid therethrough, means for connecting said system with said starting cylinder,

a manually operated valve in said system for controlling the supply of pressure to said starting cylinder, a second valve controlling the supply of fluid pressure from 20 said system to said main cylinder and automatically opened by fluid pressure when the latter reaches a predetermined point in the starting cylinder.

In testimony whereof, I have signed my 25 name to this specification in the presence of two subscribing witnesses.

FRANKLIN J. PERKINS.
